CLAIM

The ornamental design for a rechargeable Bluetooth earbud, as shown and described.

DESCRIPTION

FIG. 1 is a perspective view of a rechargeable Bluetooth earbud showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is a perspective view of the rechargeable Bluetooth earbud where the rechargeable Bluetooth earbud is in a configuration of use.

The broken lines shown in FIGS. 1-8 illustrate portions of the rechargeable Bluetooth earbud that form no part of the claimed design. The broken lines illustrating the case and extra rechargeable Bluetooth earbud in FIG. 9 are environment, while the remaining broken lines in FIG. 9 illustrate portions of the rechargeable Bluetooth earbud that form no part of the claimed design.
